CLAIM

The ornamental design for a pet feeder, as shown and described.

DESCRIPTION

FIG. 1 is a front elevational view of a pet feeder, showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a right side perspective view thereof;

FIG. 8 is a left side perspective view thereof;

FIG. 9 is a rear side perspective view thereof; and,

FIG. 10 is a bottom side perspective view thereof.
